UNITED STATES PATENT OFFICE.

EDWARD H. JOHNSON, OF AXTELL, NEBRASKA.

LOCK.

Application filed April 8, 1924. Serial No. 705,058.

To all whom it may concern:

Be it known that I, EDWARD H. JOHNSON, a citizen of the United States, and resident of Axtell, in the county of Kearney and State of Nebraska, have invented certain new and useful Improvements in Locks, of which the following is a specification.

My present invention relates to a lock or latch for doors of either the swinging or 10 sliding type.

The principal object of the invention is the provision of means as above which may be used temporarily as a latch to retain the door in closed position, or as a lock to be 15 opened only by one having knowledge of its operation.

Another important object of the invention is the provision of a positively operated mechanism which will be efficient in operation and of sturdy construction. 20

To this end my invention includes a hooked keeper which projects through the stationary wall, with which a door carried bolt engages. The hooked keeper may be 25 pushed in toward the wall to locked position which causes it to straddle the bolt the enlarged end of which prevents withdrawal therefrom. The hooked keeper automatically remains in locked position until the 30 locking means is released, as will be more fully described. In addition to the locking keeper, an additional non-locking keeper is provided to temporarily retain the bolt in proximity thereto when it is not desired to lock the door.

I have illustrated in the accompanying drawings one satisfactory form of apparatus, but it is to be understood that I do not wish to be limited thereto, as this is simply 40 illustrative to exemplify the principle involved.

In these drawings:—

Figure 1 is a view showing my device in use.

Fig. 2 is a plan view, partly in section.

Fig. 3 is a side elevation.

Fig. 4 is a view on the line 4—4 of Fig. 2.

Referring now with particularity to the drawings, I have shown a wall at 1 which 50 represents the wall upon which the door is to close in either a sliding or swinging manner. Attached to the inside of the wall is a plate 2 which carries a keeper guide 3 composed of plates having parallel portions 55 4 riveted together as at 5, and right-angular portions 6 secured to the plate 2 as by rivets

7. Suitable reinforcing means, such as strips 8, may be provided to strengthen the keeper guide 3.

A keeper 9 is provided of substantial proportions, which is adapted to project through an aperture 10 in the wall 1, the projecting end of the keeper terminating in a hook 11 for a purpose more fully herein-after described. The other end of the keeper 65 is provided with ears 12 on each side thereof, one of the side surfaces of said ears being at right angles to the side of the keeper, as at 13, the other face being other than a right angle, as at 14, for a purpose later to 70 be mentioned. An upwardly extending projection 15, preferably integral with the keeper 9, projects above the top of the plates forming the keeper guide 3. The upper extremity of the portion 15 is provided with 75 an aperture 16 to which is secured one end of a coil spring 17. The other end of the spring 17 is secured to the plate 2 in any suitable manner.

An angular spring element 18 secured to 80 the plate 2 has a portion thereof bearing against the angular side 14 of the ears 12 on the keeper 9. That portion of the spring element 18 just referred to is also provided with an eyelet 19 to which is attached a release wire 20 extending to any desirable location remote from the lock.

The door which cooperates with the wall 1 is illustrated at 21, to which is attached in a revolvable manner a bolt 22 having an enlarged head 23. 90

The operation of the device is as follows: If pressure is put on the release wire 20 the spring element 18 is pulled away from the ears 12, which causes the end of the element 95 to clear the extreme face 13 of the ears 12 with the result that spring 17 is allowed to function and causes the keeper to project through the aperture 10 in the wall to any desired extent, determined by the slot 24 100 in the plates forming the keeper guide. In this position the door is then made to approach the wall and the bolt may then be revolved so as to fall within the hooked end 11 of the keeper. If it is now desired to 105 lock the door in this position, pressure may be exerted along the axis of the keeper 9 against the tension of the spring 17 so that the ears 12 clear the end of the spring element 18 which snaps against the keeper 110 back of the right-angular face 13. At this position the end of the hook 11 is within 110

the aperture 10 in the wall and the bolt cannot be removed from the hook, and the door is securely locked in closed position. A guard plate 25 may surround the keeper 9 and the aperture 10 through which it projects on the outside of the door to prevent the bolt from being forced from the hook.

As a temporary latch the hooked keeper 9 may remain in a projected or unlocked position and the bolt 22 on the door 21 swung over to engage a temporary keeper 26 having a slot 27 therein. This slot 27 will effectively prevent removal of the headed bolt therefrom accidentally, although this mechanism serves merely as a latch.

I contemplate if for instance the lock is used on a barn door, extending the release wire 20 to a point outside of the barn and away from the door so that the device requires no key, but the keeper may be released by pulling on the wire 20, the location of which will only be known to one authorized to enter the barn or other housing.

Having thus described my invention, what I claim is:

1. In combination a wall, a lock mechanism attached thereto, including a hooked keeper penetrating said wall and at right angles thereto, and spring means to project said keeper to the outside of said wall, lugs on said keeper, and spring retaining means adapted to engage said lugs and rendering ineffective said keeper projecting means.

2. In combination a wall, a lock mechanism attached thereto, including a hooked keeper penetrating said wall and at right angles thereto, a door, a swinging bolt carried thereby, said bolt slidably engaging the hooked end of said keeper.

3. In combination a wall, a lock mechanism attached thereto, including a hooked keeper penetrating said wall and at right angles thereto, a door, a swinging bolt carried thereby, said bolt slidably engaging the hooked end of said keeper, with an additional keeper adapted to engage said bolt to retain door and wall together when the hooked keeper is in its outermost projected position.

In testimony whereof, I affix my signature,

EDWARD H. JOHNSON.
